(57) **CLAIM**

The ornamental design for a mobile device holder, as shown and described.

DESCRIPTION

FIG. 1 is a perspective view of a mobile device holder according to the present design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a second perspective view thereof, illustrating a foldable element thereof open.

The portions of the article shown in broken lines in FIG. 7 are provided for illustrative purposes and do not form part of the claimed design. The entire bottom surface of the article forms no part of the claimed design.

1 Claim, 6 Drawing Sheets
